United States Patent Office

Des. 226,337
Patented Feb. 13, 1973

226,337

DESK SET

Roland P. Longarzo, 218 Hollywood Ave.,
Valley Stream, N.Y. 11580

Filed Jan. 10, 1972, Ser. No. 216,877

Term of patent 14 years

Int. Cl. D19—06

U.S. Cl. D74—5 B

FIG. 5

FIG. 2

FIG. 4

FIG. 1

FIG. 3

FIG. 6

FIG. 7

FIG. 8

FIG. 1 is a perspective view of a desk set showing my new design;

FIG. 2 is a top plan view of the base portion thereof;

FIG. 3 is a bottom plan view of the base portion;

FIG. 4 is a side elevational view of the base portion as it appears with the pen receptacle rotated to upright position;

FIG. 5 is a front elevational view thereof, the back being similar except for the omission of the front cut-out;

FIG. 6 is a side elevation of the combined writing instrument and dialer portion;

FIG. 7 is a left end view thereof; and

FIG. 8 is a right end view thereof.

I claim:

The ornamental design for a desk set, substantially as shown and described.
